TRAVELING BLOCK

Oswald Duda, Corsicana, Tex., assignor to American Well & Prospecting Company, a corporation

Application February 26, 1938, Serial No. 192,718

1 Claim. (Cl. 254—197)

My invention relates to sheaves or traveling blocks such as are employed in hoisting mechanism for lifting loads. It is particularly adapted for use as a traveling block in oil field operations in which the loads to be handled are largely pipe and the like.

In the use of sheaves or traveling blocks of this character a strong steel cable is employed and it is desirable to thread the cable over each separate pulley or sheave in the traveling block in an expeditious manner. The usual method of threading the cable over the pulleys of the block is to remove the housing from about the pulleys and expose them in such manner that the steel cable may be forced around the pulley and seized upon the opposite side and brought upwardly for engaging over the upper crown block or sheave on the derrick. To disassemble the traveling block for the purpose of threading the cable therethrough is a troublesome and time-consuming operation which is to be avoided if possible.

It is an object of my invention to provide a guide around the lower side of each of the pulleys in the traveling block so that the cable will contact with the guide and be forced to travel in a path around the pulleys and to project from the opposite sides so that it may be easily handled.

I desire to provide a guide for the cable which is so mounted that the cable may be extended about the separate pulleys quickly and without removing any portion of the housing for the block.

The invention consists particularly in the features of construction of my device which make it possible to thread the cable through the block in the manner recited and reference is made to the drawing herewith for a better disclosure thereof.

In Fig. 1 I have shown a side view partly in elevation and partly in vertical section illustrating the construction of my cable guide.

Fig. 2 is a front elevation at right angles to the view shown in Fig. 1 with a portion of the housing or guard broken away and the parts in central vertical section showing the use of my invention.

My device is adapted to be used upon any ordinary type of traveling block. I have shown a form of traveling block in some detail but it is to be understood that the device is intended for use generally upon blocks of this character.

In the drawing herewith the pulleys or sheaves 1 are mounted for rotation on a transverse shaft 2. Said shaft 2 is mounted in a frame including two opposite side plates 3 which are of strong steel plates and furnish a firm support for the shaft. Between the two side plates 3 are inter-

mediate plates 4 which act to strengthen the device and also to separate each individual pulley from the adjacent pulley or sheave. There will be as many of these intermediate plates or webs 4 as are necessary in the formation of the particular block involved.

At each end the side plates and the intermediate plates are formed with openings to receive a transverse pin 5 at the upper end and 6 at the lower end. The upper pin 5 is extended through the said plates which are separated by spacers 7. The plates and spacers are locked in assembled position by a nut 8 upon the shaft which may be held against rotation by a cotter pin 9.

At the lower end the transverse pin 6 is extended through the plates in the same manner as has been described. Spacers 10 are employed to separate the intermediate plates but the two outer plates are spaced from the adjacent plate by a clevis or hook 11, said clevis extending down below the transverse pin and serving as a connection with the swivel or other load. Between the two upper arms of the clevis I prefer to use a sleeve or bushing 12 as a spacer between the arms of the clevis. The pin 6 is held in position by a nut 13 and cotter pin 14 in the usual manner.

As is desirable in traveling blocks of this character the sheaves and plates are housed about by a casing or guard 15. In the embodiment shown the housing is formed in two side sections which overlap the side plates 3 along their inner margins and the sections of the housing are held in position by through bolts or pins 16 at the upper and lower ends. At the sides of the housing adjacent each of the pulleys there is a slot indicated at 17 formed in the housing to allow the cable to run therethrough and over the pulleys. These slots extend from the upper end of the housing down short of the shaft 2. This housing forms a guard which shields the operator from contact with the pulleys and also protects said pulleys from contact with other objects in use which might damage them.

The end of the cable is intended to be inserted through the slots 17 about the pulleys and in order to guide the end of the cable around the pulley I form upon each of the spacing plates 4 an arcuate guide member indicated at 18 in the drawing. With reference particularly to Fig. 1 it will be noted that this guide member is formed integral with the spacer 4 by means of welding or otherwise and extends from the side of the plate laterally in the arc of the pulley and into contact with the side wall of the housing at 19. The

guide 18 is preferably reenforced somewhat on its lower side by webs 20 so that there will be no danger of breakage in the handling of the cable.

5 As will be noted from Fig. 1, the partition plates 4 are not the full width of the housing but form supports for the sheaves. The lateral portions of the guide member 18 extends laterally away from the plates and upwardly around the sheave 10 and in position spaced slightly from the periphery of the sheave.

In the threading of the cable through the pulley it will be obvious that the end of the cable although it is fairly stiff and not very pliable may be forced downwardly around the outer periphery of the pulley through one of the slots 17. It will engage with the guide member 15 and by rotating the pulley the cable may be drawn around the lower end and forced upwardly so that it will protrude from the opposite slot 20 17 where it may be seized and drawn through the traveling block and then extended upwardly over the crown block and back again to the traveling block. Each time the cable may be 25 threaded around the pulley in the housing in the manner stated.

This construction of my improved traveling block which enables the cable to be threaded around the separate pulleys of the block is a 30 time and labor saving device which is particularly valuable. It will not be necessary to re-

move any portion of the housing from about the block and it has been found to be particularly easy to force the end of the cable around the pulley in this manner and the time consumed is slight. It will be obvious also that the guide member 5 retains the cable in spaced relation close to the pulley so that when the line is slack there is no tendency of the cable to move away from the periphery of the sheave. The further advantages of this device will be obvious. 10

What is claimed is:

A traveling block construction including a block having a plurality of spaced separator plates therein, a flange extending laterally to one side of each separator plate, a web beneath each flange connecting the flange to the plate and to reenforce the flange, a cable sheave rotatably mounted in said block adjacent each plate and above each flange, each flange being curved to follow the periphery of said sheave, and guard 15 casings, one on each side of said block enclosing said sheaves and plates to overlie the edges of said sheaves and abut the ends of said flanges, and slots in the upper portion of said casings at the edges of the sheaves so that a cable being 20 reeved thru said block will move down along the casing to engage said flange and then along the flange around the sheave to be guided upwardly by the opposite casing to the opposite slot. 25
